UNITED STATES PATENT OFFICE.

WILLIAM S. MCKENNA, OF PITTSBURG, PENNSYLVANIA, ASSIGNOR TO
HARBISON & WALKER, OF SAME PLACE.

FIRE-BRICK.

SPECIFICATION forming part of Letters Patent No. 274,357, dated March 20, 1883.

Application filed January 29, 1883. (No model.)

To all whom it may concern:

Be it known that I, WILLIAM S. MCKENNA, a citizen of the United States, residing at Pittsburgh, county of Allegheny, State of Pennsylvania, have invented or discovered a new and useful Improvement in Fire-Brick; and I do hereby declare the following to be a full, clear, concise, and exact description thereof, reference being had to the accompanying drawings, 10 making a part of this specification, in which—like letters indicating like parts—

Figure 1 is a perspective view of my improved fire-brick, and Fig. 2 illustrates on a smaller scale a number of such bricks built up 15 as in forming checker-work for a regenerator-furnace.

My invention relates to certain improvements in fire-brick designed for use in forming the checker-work of regenerator-furnaces; and, in 20 general terms, it consists of a fire-brick, cubical in general form, having notches formed in its sides and in one edge, the bottoms of which incline or converge toward the central line of such edge, thereby forming an alternate succession of flat and of wedge-shaped faces, as 25 hereinafter more fully described and claimed.

In building the checker-work of regenerator-furnaces it is desirable to avoid upward exposure of flat surfaces, for such surfaces form 30 lodging-places for cinder, soot, and ashes, thereby choking the open spaces and impairing the efficiency of the furnace. This object is ordinarily accomplished by making the bricks wedge-shaped and laying them with the sharp 35 edge or ridge upward. Provision has also been made for a flat face on which to rest the cross-courses by cutting down the ends of the wedge-shaped ridges, forming depressed shoulders below the apex of the ridge. Bricks made in this 40 form are difficult to stack or pack for shipping, and the wedge-shaped ridges are liable to be broken or chipped off, being unprotected and exposed to such injuries; also, when the ends of the ridges are cut down to form flat bearing- 45 faces for the cross-courses the open spaces of the checker-work are materially reduced, which is a serious objection. With bricks having the wedge-shaped ridge continued through the whole length, the upper courses rest upon the 50 ridges or sharp edges of those below, giving

a comparatively small bearing-surface. These ridges, when heated, become more or less plastic, permitting the work to settle and the bricks to stick together, thereby rendering them unfit for use a second time in case rebuilding the 55 checker-work becomes necessary.

The purpose of my invention is to overcome these defects or objectionable features in the construction of the bricks, and this I do by means of bricks A, of cubical form in general 60 outline, which may be of any desired length and size of section, but by preference having a length four times its thickness or width of edge, so that the surface of the edge may be divided into four squares. One such square, a, 65 is made at the center, a half-square, a', at each end, and between these flat faces notches c c are made in pairs or opposite each other in the sides and edge. These notches have inclined 70 or sloping bottoms converging toward the central line of the flat faces a a', forming wedge-shaped ridges c', the sloping sides of which extend well down the side faces of the brick by making the flat faces a a' the full height of the brick, and on either side of the ridges c' the 75 latter are protected from danger of chipping or breaking; also, these flat faces facilitate packing, handling, and shipping, affording substantially the same advantages in these respects 80 as full cubical bricks.

In laying these bricks for checker-work the successive courses are laid across the flat faces a a', as illustrated in Fig. 2, leaving only the sloping faces c and comparatively sharp ridges c' exposed to falling soot, ashes, &c. As great 85 stability and area of support is secured in this way as though the bricks were of cubical form throughout, and also the full advantages are secured of sloping the walls which have upward exposure without any of the disadvantages which have attended handling, shipping, 90 and laying this class of bricks as heretofore made.

My improved bricks may be made by pressing the clay in molds, and subsequently treating them in manufacture as commonly practiced in the art.

While I prefer the proportions of size and arrangement of flat and inclined faces, as shown 95 and described, still these features may be va- 100

ried without departing from my invention. For example, the length of bricks may be increased or diminished, and sloping notches c be made in the middle instead of the flat face a ; also, the 5 side edges, c^2 , of the notches may be sloped, thereby increasing the width of the notch upward to afford more draft to draw the brick readily from the mold; or the flat faces a a' may be made of other forms than those shown— 10 for example, by increasing the width of the notches on one or both sides. This, however, would reduce the bearing-surface of the cross-courses, and is therefore objectionable. By making half-square faces a' at the ends of the 15 full height of the ridges c' laying the bricks to break joints is facilitated, and also the ridges are protected much better than in bricks having the outer corner of such ridges exposed, as heretofore. These features of improvement 20 are of material importance and advantage, and adapt such bricks much better to the purposes for which they are designed.

I claim herein as my invention—

1. A fire-brick of cubical form, having on one 25 edge a succession of flat and of inclined or wedge-shaped surfaces, the latter being below the plane of the former, substantially as and for the purposes set forth.

2. A fire-brick, A, of cubical form, having sloping notches c in its sides and edge at intermediate points in its length, substantially as and for the purposes set forth. 30

3. A fire-brick, A, of cubical form, having on one edge flat end portions, a' , and intermediate wedge-shaped portions, c c' , the flat portions being the full height of the wedges c' , substantially as and for the purposes set forth. 35

4. A fire-brick, A, of cubical form, having in the plane of one edge a central flat portion, a , and flat end portions, a' , with intermediate 40 wedge-shaped portions, c c' , substantially as set forth.

5. A fire-brick, A, of cubical form, having in the plane of one edge a central square surface, a , and half-square end surfaces, a' , with 45 intermediate wedge-shaped or sloping surfaces, substantially as and for the purposes set forth.

In testimony whereof I have hereunto set my hand.

WILLIAM S. MCKENNA.
